UNITED STATES PATENT OFFICE

2,008,681

HINGED CLAMP SAFETY RAZOR HOLDER

Axel S. Carlson, New York, N. Y., assignor of one-half to Concetta L. Blue, Brooklyn, N. Y.

Application January 3, 1934, Serial No. 705,081

14 Claims. (Cl. 30—12)

My invention relates to a clamping device for a safety razor blade in which the under side of the blade is supported on a fixed and rigid supporting plate attached to a handle, and in which the blade is clamped in place by a hinged clamping plate which is hinged on one end of the supporting or holding plate.

In this type of construction, one of the objects and features of my invention is in the manner of hinging or pivoting the clamping plate which is done by means of a pinion connected to the pivot shaft of the hinge on the clamping plate, and the pinion is rotated by a sliding rack slideable longitudinally of the lower supporting or holding plate. Further, the rack is moved by means of a wedge reciprocated longitudinally of the hinge, the wedge being moved by a nut on the end of the handle engaging a screw on a stem which holds the wedge; thus, by rotating the nut in one direction of rotation relative to the handle, the stem with the wedge is raised and moves the rack outwardly, thereby rotating the pinion shaft to swing the clamping plate from a position parallel to the holding plate, to a position at right angles thereto, which clamp may be turned for convenience to a vertical position.

Another detailed feature of my invention relates to a slip hinged connection by providing an arm on the clamping plate with slots engaging the hinge pivot to accommodate razor blades of varying thickness. Another detail is a limiting stop finger for retaining the clamping plate in its vertical position when the holding plate is in the horizontal position for removing and inserting blades.

Another feature of my invention relates to a pressure device used to exert a pressure on the clamping plate to hold the blade tightly between the clamping and holding plates, and this also has a function of preventing or permitting hinging of the clamping plate. Such construction includes the stem longitudinally movable in the handle and actuated by the nut and thread above mentioned. The stem, however, has a single or partial thread connecting it one-quarter of a turn, preferably by use of a squared stem having a one-quarter twist and operating through a fixed squared opening. The upper end of the stem has an elongate somewhat rectangular head or knob which passes through a slot in the plate, and an aligned slot in the clamping plate. When the knob is crosswise and pulled downwardly, it clamps the clamping plate and blades, and when rotated one-quarter of a turn, it permits

the clamping plate in its arcuate movement to pass over the sides of the knob.

Other detailed features of my invention relate to the manner of supporting and centering the blade as well as a construction facilitating removal and replacement of the blades, and further a hand grip device on the handle which has a frictional grip on the handle but allows relative rotation so that the blade may readily follow the curves of the face and neck in shaving.

My invention is illustrated in connection with the accompanying drawings in which:

Fig. 1 is an end elevation taken in the direction of the arrow 1 of Fig. 2.

Fig. 2 is a side elevation taken in the direction of the arrow 2 of Fig. 1.

Fig. 3 is a plan taken in the direction of the arrow 3 of Fig. 2.

Fig. 4 is a vertical transverse section on the line 4—4 of Fig. 3 in the direction of the arrows 20 on a larger scale.

Fig. 5 is a longitudinal section on the line 5—5 of Fig. 4 in the direction of the arrows.

Fig. 6 may be considered as a transverse horizontal section on the line 6—6 of Fig. 5, illustrating mainly, the blade and its supporting structure.

Fig. 7 is a detailed end elevation taken in the direction of the arrow 7 of Fig. 5.

Fig. 8 is an elevation similar to Fig. 2 with the clamping plate elevated.

Fig. 9 is a transverse section of the line 9—9 of Fig. 1 in the direction of the arrows.

Referring first to Figs. 1, 2 and 3, the razor employs a holding or supporting plate 11 which is rigidly connected to a handle 12. This handle is provided with a cylindrical section 13 and a rotatable nut 14 at the end, the nut being knurled on its outside surface. The razor blade 15 rests on the supporting plate and is held in place by a clamping plate 16, which plate has an arm 17 on one end engaging the ends of the hinge designated by the assembly numeral 18.

The blade construction is provided with two parallel cutting side edges 19, right angular ends 20, and an extending finger gripping end 21, this end having a concaved curve 22. The blade is provided with a longitudinal slot 23 having a pair of inwardly projecting shoulders 24. The slot is rounded at the end 25 and has a center section 26 with curved sides, and adjacent thereto, straight sides 27, from the shoulders 24. The ends 20 of the blade are engaged by outwardly extending end projections 28 from the supporting plate, these being spaced apart. These projec-

tions also engage longitudinal shoulders 29 of the blade (note Fig. 6). The blade rests on a pair of transverse ribs 30 extending substantially completely across the supporting plate, which 5 plate has a pair of parallel sloping grooves 31 inside of the guard comb 32, this guard comb having individual guard teeth 33. The ribs 34 (note Fig. 6) have upward projections 35 extending upward in the slot 23 between the shoulders 10 24. Partial ribs 36 extend partly across the clamping plate adjacent the end projections 28. A fixed stop 37 is screw-threaded into the supporting plate and extends upwardly through the slot 23 adjacent the curved ends 25. The blade 15 thus when properly centered on the supporting plate is held in a definite position and cannot shift lengthwise or laterally.

The clamping plate 16 is provided with a series of transverse ribs 38 which engage the blade 20 when in the clamped position vertically above the various ribs on the supporting plate. The clamping plate has a pair of end ribs 39—40 which are slightly shorter than the ribs 38 and do not engage the plate.

25 The construction of the hinged connection of the clamping plate to the supporting plate is as follows:—

Two bearings 41 are attached by means of screws 41' to one end of the supporting plate, 30 and through these bearings there extends a pivot or hinge shaft 42, the center portion of which has a pinion 43. The end portions of the pivot shaft are flattened as indicated at 44, and engage in slots 45 in the ends of the arms 47. These arms 35 each have a projecting finger 46 and the slots allow a slight relative movement of the clamping plate and the hinge.

The under side of the supporting plate is provided with a longitudinal groove 47 extending 40 from one end to slightly beyond the center. In this groove there is a slidable rack bar 48 having the rack teeth 49 at the outer end engaging the pinion 43.

45 The inner end of rack bar 48 is provided with a block 50 which operates through openings 51 in the upper portion of the handle. This block has a vertical center opening 52 with diverging sloping surfaces 53 and 54. Each surface terminates at the bottom 55 of the block in a comparatively sharp edge 56 and 57 respectively. Cooperating with this construction the handle 50 12 has an inner sleeve 58 with a flange 59 at the top secured to the under side of the supporting plate. An outer sleeve 60 surrounds the inner sleeve 58. Both of these sleeves have the transverse openings 51 and the inner sleeve 58 has a longitudinal slot 61 forming a guide way. The inner sleeve 58 is provided with a bottom plate 62 which has a square opening 63 therethrough.

60 The wedging device designated by the assembly 64 for operating the rack bar is as follows:—

A wedge block 65 is mounted on a stem 66, this stem having a cylindrical section 68. The wedge block has a sloping surface 69 adapted to engage 65 the edge 56 of the block 50 when the rack bar is retracted and force this bar outwardly when the wedge block is raised, the raising action being as hereinunder detailed:—

70 The wedge block is held firmly in position by means of a lower collar 70 with an upper collar 71, and two marginal edges 72 operate in the guide slots 61 of the inner sleeve 58. On the upward movement of the wedge block, the return wedging surface 73 moves contiguous to the wedging surface 54. When the wedging block moves

upwardly it thrusts the rack bar to the right, (having reference to Fig. 5), and thus rotates the pinion and elevates the clamping plate to the position shown in Fig. 8. The reverse movement is given by pulling down on the wedging block and in this case the surface 73 bears on the complementary sloping surface 54 of the block 50 of the rack bar and returns this rack bar to the left, this closing the clamping plate into clamping relation to the supporting plate.

10 The wedging block is actuated by means of the knurled nut 14, which nut has internal threads 74 engaging a single thread or pin 75 on the lower end of the stem 76. The nut and the handle 13 which has the sleeve 60 are assembled by providing the nut with an annular groove 77 and the end of the sleeve with an inwardly compressed rim 78 (note Fig. 5); thus, when the nut is rotated, the squared portion 79 of the stem operating through the squared guide 33 prevents the 20 stem from rotating except when the quarter turn or twisted section 80 passes through the squared opening. The action therefore of rotating the knurled nut is to raise and lower the wedging device 64.

25 The pressure device utilizes a tension rod 81 which forms a continuation of the stem. It passes through a cylindrical opening 81' in the supporting plate, through the center of the slot of the razor blade and through a narrow rectangular slot 82 of the clamping plate 16. The upper end of the tension rod 86 is provided with a knob or head 83, this being rectangular and having a narrow dimension indicated at 84, less than the width of the slot 82, and a long measurement indicated at 85 longer than the width of the slot. The knob is also preferably tapered as indicated at 86 (note Fig. 4) to engage complementary sloping surfaces of the slot 82.

30 The action and function of the knob 83 with the tension rod 86 connected to the stem is as follows:—

35 When the blade is clamped as shown in Fig. 5, the nut 14 gives a downward pull on the pin 75 and this pulls on the knob 83 which is crosswise to the slot 82; thus the clamp plate is pulled downwardly into tight engagement with the blade and presses the blade on the supporting plate. When it is desired to lift the clamping plate for removing or inserting a blade, the rotation of 40 the knob 14 in a direction to raise the pin 75 first loosens the pressure of the knob on the clamping plate and then in a further elevation of the stem, gives this a one-quarter turn rotation due to the one-quarter square thread turn 88. This action 45 rotates the knob so that the length of the knob is lengthwise of the slot 82. As soon as the knob has been turned, a further upward movement of the wedging device 64 having the block 65 operates the rack bar and swings the clamping plate 50 upwardly into the position of Fig. 8. This clamping plate is returned to its clamping position and then the knob rotated and pulled downwardly by a reverse series of motions.

55 An additional hand grip device 90 employs a lower collar 91 which encircles the lower portion of the cylindrical section 13 of the handle, and an upper clamping collar 92. A lateral hand grip 93 extends between the collars and outwardly from the handle section 12. The clamping collar 70 has a fixed section 93 and a movable strap section 94 which is secured by a rivet 95 to the handle 32. A pin 96 extends through an opening in the handle and is riveted or otherwise secured at 97 to the section 94 and has a button 98 for pressing 75

the pin and thus releasing the clamp collar 91, to facilitate rotation of the handle 12 within the collars 90 and 91.

The end of the clamping plate opposite the hinge has a cut-out section 99 to facilitate grasping the extending ends 21 of the blade for inserting and removing the blade.

Various changes may be made in the details of construction without departing from the spirit or scope of the invention as defined by the appended claims.

I claim:

1. A safety razor having a handle, a supporting plate secured thereto at right angles to the handle, a clamping plate pivotally connected to the supporting plate at one end, said clamping plate having a slot therethrough, a blade having a perforation, means operatively connected to the handle to rotate the clamping plate on its pivot, 20 and a stem slidably mounted in the handle and extending through the perforation in the blade and through said slot and having means to engage the clamping plate to clamp the blade tightly between said plates.
2. A safety razor having a handle with a bore extending therethrough, a supporting plate connected to the end of the handle, a clamping plate having a slot therethrough, said plate being pivotally connected to the supporting plate at one 30 end, means on said plates adapted to engage a blade, a stem extending through said bore and adapted to pass through said slot, means to exert a tension on the stem to secure the clamping and supporting plate, means operatively connected to the handle to rotate the clamping plate on its pivot, and means on the stem to actuate the means for moving the clamping plate in one direction.
3. In a safety razor, a supporting plate, a clamping plate hinged thereto at one end, a blade 40 mounted on the supporting plate, and a rack and pinion for rotating the hinge and the clamping plate to swing the clamping plate in an arc, the supporting plate having a handle at right angles thereto, a stem extending through the handle, the clamping plate having a slot therethrough, the stem extending through the slot and being provided with a head, and means to longitudinally move the stem and rotate the stem to engage the head with the clamping plate.
4. In a safety razor, a supporting plate, a clamping plate hinged thereto at one end, the said plates being adapted to engage a blade therebetween, the pintle of the hinge having a pinion, a rack slidably mounted on the supporting plate 50 to actuate the pinion, a handle connected to the supporting plate and a slidable means in the handle to actuate the said rack, the clamping plate having an elongated slot, a stem extending through the slot and through the handle, the said stem having a knob, and means to rotate the stem to pass the knob through the slot or to engage the clamping plate by the knob and means to exert a tension on the stem.
5. In a safety razor, a supporting plate, a clamping plate hinged thereto at one end, the plates being adapted to clamp a blade therebetween, a slidable rack on the supporting plate, a pinion connected to the hinge to actuate the same, a handle on the supporting plate having a stem 60 therein, and a wedging means on the stem co-acting with a complementary wedge device on the rack to reciprocate said rack, the wedging means on the stem comprising a wedge block having a pair of sloping surfaces, the wedging device on the rack having a block with a sloping

surface to engage one of the surfaces of the wedging block, and an edge to engage another surface of said block.

6. In a safety razor as claimed in claim 5, the clamping plate having an elongated slot, the stem extending through said slot and having a head on top, the head being longer than the width of the slot, means inter-connected with the stem to rotate the stem and hence the knob one-quarter turn in reciprocation of the stem, and means to exert a tension on the stem to clamp the plate when in its blade engaging position.

7. A safety razor having a supporting plate with a tubular handle at right angles thereto, a clamping plate hinged thereto at one end, the said plates being adapted to engage a razor blade therebetween, a pinion forming part of the hinge, a slidable rack on the supporting plate and having a wedge block with an internal sloping surface and an edge, a slidable stem in the handle having a movable wedge block thereon, and a pair of sloping wedge surfaces, one to engage the surface and the other to engage the said edge of the wedge block of the rack, and means to reciprocate the stem to turn the clamping plate in an arc.

8. A safety razor as claimed in claim 7, the clamping plate having an elongated slot, the said stem extending through the slot and having a flattened head of greater length than the width of the slot, and means to reciprocate the stem comprising a nut on the handle engaging the thread on the stem and means co-acting with the stem to rotate the stem one quarter turn during each reciprocation.

9. A safety razor having a supporting plate with a tubular handle, a clamping plate connected thereto at one end, said clamping plate having an elongated slot therethrough, a stem extending through the handle through the supporting plate and the said slot, said stem having a head of greater length than the width of the slot, means operatively connected to the handle to reciprocate the said stem, means engaging the stem to rotate the stem one-quarter turn, and means cooperating with the stem to swing the clamping plate through an arc.

10. In a safety razor having a cylindrical handle, a hand grip device having a pair of collars surrounding the handle, one of said collars having a releasable clamp to release said latter collar from the handle.

11. In a safety razor, a tubular handle, a supporting plate having a perforation, a clamp plate having a slot, a blade having a slot and located between the said plates, a nut rotatable on the handle, a stem having a thread in the nut, said stem passing through the said perforations and slots, a head on the stem of greater length than the width of the slot and means in the handle to rotate the stem and head one quarter of a turn when said stem is moved longitudinally by the nut, a wedging means mounted on the stem, means to retain the wedging means from rotation, a pivot connecting the clamping plate to the supporting plate and a moving means mounted on the supporting plate and actuated by the wedging means to rotate the clamping plate on its pivot.

12. In a safety razor, a tubular handle, a supporting plate having a perforation, a clamping plate having a slot, a blade located between the said plates and also having a slot, a nut rotatable on the handle, a stem having a thread in the nut, said stem having a one quarter turn thread above

the nut, means in the handle engaging said latter thread, the upper end of the stem passing through the said perforation and slots, a head on the stem of greater length than the width of the slot in the clamping plate, the said nut on rotation moving the stem longitudinally and the one-quarter turn thread of the stem causing a one-quarter turn rotation of the stem to turn the head of the stem between a position aligned with the slot of the clamping plate and a position transverse thereto.

13. In a safety razor as claimed in claim 12, a pivot connecting the clamping plate and the supporting plate and having a pinion, a rack slideable longitudinally of the supporting plate to operate the pinion, a wedging means mounted on the stem, means in the handle to prevent rotation of the wedging means on rotation of the stem the said wedging means engaging the said rack on

upward movement of the stem to move the rack and swing the clamping plate into an open position relative to the supporting blade.

14. In a safety razor, a supporting plate having a perforation, a clamping plate having a slot, said plates being adapted to clamp a blade therebetween, a hollow handle connected to the supporting plate, a stem extending through the handle, the perforation and slot, and having a head on the top, the head being longer than the width of the slot, means to move the stem longitudinally and at the same time means inter-connected with the stem to rotate the stem and hence the head one quarter turn, the said moving means for the stem being adapted to exert a tension on the stem to clamp the clamping plate when in its blade engaging position.

AXEL S. CARLSON.
